UNITED STATES PATENT OFFICE

ROBERT E. MCCLURE, OF WARREN, OHIO

DESIGN FOR A GAME BOARD

Application filed July 18, 1931. Serial No. 40,594. Term of patent 3½ years.

To all whom it may concern:

Be it known that I, ROBERT E. MCCLURE, a resident of Warren, county of Trumbull, State of Ohio, have invented a new, original, and ornamental Design for Game Boards, of which the following is a specification, reference being had to the accompanying drawing forming a part thereof in which the figure is a plan view of a game board showing my new design.

The design shown is a surface design and the game board has a thickness of cardboard commonly used in the manufacture of games of the class to which the invention relates.

I claim:—

The ornamental design for a game board as shown and described.

In testimony whereof I hereunto affix my signature.

ROBERT E. MCCLURE.
